UNITED STATES PATENT OFFICE.

AUGUST W. REILING, OF FORT WAYNE, INDIANA.

CAR-CONTROLLING APPARATUS.

No. 895,109.

Specification of Letters Patent.

Patented Aug. 4, 1908.

Application filed March 25, 1907. Serial No. 364,250.

To all whom it may concern:

Be it known that I, AUGUST W. REILING, a citizen of the United States, residing at Fort Wayne, in the county of Allen and State of Indiana, have invented a new and useful Improvement in Car-Controlling Apparatus, of which the following is a specification.

This invention relates to apparatus or systems for controlling the movement of a car or train. Its object is to provide an arrangement whereby the car or train may be stopped or otherwise controlled independently of the train crew when the track ahead is in a condition of danger, the means for accomplishing the end or result being very simple in construction and very efficient in operation.

It consists in the novel features of arrangement and construction hereinafter described and shown in the drawings.

Many accidents on railways have been caused by the engineer failing to observe or obey the danger signals set against him by the operator, and the object of my invention is to provide a simple and efficient means whereby the operator may control the car or train should the latter pass onto the track ahead which is in an unsafe or dangerous condition.

I contemplate using my invention with all cars to which it may be applied and for the purposes of illustration I have shown it as adapted to a locomotive.

Referring to the drawings Figure 1 is a diagrammatic view of my invention as applied to a railway; Figs. 2, 3, 4, 5, 6, 7, 8 and 9 are details.

I have shown a locomotive 1 provided with an ordinary air brake system, the train pipe 2 of that system being the only portion illustrated. A branch pipe 3 connected to train pipe 2 leads to a suitable pressure relief means 4, which is adapted to relieve the air pressure in the train pipe and apply the brakes in the usual manner.

Suitably mounted on the locomotive in proximity to means 4 is an electro-tripping magnet 5 whose armature 6, when the magnet is energized, is adapted to strike and raise a latch 7 which engages a valve actuating lever 8. For compactness I prefer to mount the magnet within a pipe or tube 9, means 4 being mounted on one end of this tube; latch 7 protrudes through a suitable opening 10 in the pipe and lever 8 is suitably

pivoted on a standard 11, which is preferably carried on means 4 and held thereon by a part 12, through an opening 12' in which part passes one arm of lever 8. To prevent the unintentional releasing of latch 7, as, for example, by jarring, I provide a lever 7^a which is pivoted to pipe or tube 9, one arm 7^b of which engages latch 7, the other arm 7^c extending between armature 6 and latch 7. Latch 7 cannot be released except by armature 6, which will move both lever 7^a and the latch when the magnet is energized. A suitable means, such as spring 13 within part 12, opposes lever 8 and causes it to actuate means 4 when latch 7 is released by the magnet.

Any suitable pressure relief means will answer my purpose. It is advantageous to provide a relief means which can be quickly and easily operated against the fluid pressure which holds it on its seat; that is, the air brake train pipe pressure. In the drawings I have shown, as one such means, a check valve 4, having the usual casing 14, which is provided with a partition 15 therein dividing the interior into inlet and exhaust chambers 15^a and 15^b respectively, and suitable inlet and exhaust openings 16 in one of which openings is fitted branch pipe 3 so as to admit the air pressure from the train pipe into inlet chamber 15^a. A valve 17 passes through a suitable opening in partition 15, the periphery of which opening is suitably prepared to form a seat 18 for a companion surface on the valve. Branch pipe 3 being connected to the casing in opening 16 so as to admit the air pressure from the train pipe into inlet chamber 15^a, the air pressure is therefore effective over the under portion of valve 17 and holds it tight on seat 18. To relieve the pressure in chamber 15^a and in the train pipe to apply the brakes, valve 17 must be moved off seat 18 against the train pipe pressure which is usually 80 or 90 pounds per square inch. To assist in the rapid movement of this valve I make the interior of valve 17 hollow and loosely place within it another valve 19 having its seat 20 on valve 17, preferably at one end thereof. An opening 21 in valve 17 permits of communication between the interior of that valve and exhaust chamber 15^b. The stem of valve 19 projects beyond the stem of valve 17 so that it may first receive the pressure of lever 8. When lever 8 forces valve 19 off its seat the air rushes into the interior.

of valve 17 and out through opening 21. This immediately relieves the pressure on valve 17 so that the pressure of lever 8 drives valve 17 off its seat very quickly and easily. 5 Since valve 19 has only a small area exposed to the train pipe pressure, it requires a small amount of pressure to move it as compared to that which valve 17 would require; consequently I am able to use an electro-tripping magnet and electric current of comparatively small power and also use a less powerful means to force lever 8 against the valve when the lever is released by the magnet. It is desirable in practice, to provide a 15 means whereby the operation of the pressure relief means shall be regulated or controlled so that any desirable degree of application of the train pipe pressure from a mere signal to the emergency application may be achieved. 20 In passenger trains it would probably be desirable to apply the emergency brakes; that is, release the entire train pressure, while in freight trains it would be desirable to provide an ordinary train stop application of the 25 air to prevent the buckling of the train in the middle, which buckling might occur if an emergency application of the air was made, or it might be desirable to provide a mere signal to the engineer by a slight exhaust of the air pressure in the relief means. 30 This result may be accomplished in many ways. I show one manner of controlling the movement of relief means 4 by limiting the throw of lever 8. I accomplish this by 35 the use of a suitable guide 8^a carried by pipe or tube 9 which prevents any lateral motion of lever 8. I provide this guide with a suitable adjustable abutment which may be a bolt or pin 8^b adapted to be fixed at any predetermined point in the guide, as in any of 40 the holes 8^c, the holes 8^c being placed in guide 8^a at the desirable points. When latch 7 is released from lever 8 the latter will be forced outward by opposing means 13 45 and the position of the abutment will limit the throw of that lever and consequently limit and control the motion of valves 17 and 19 so as to permit of a slight relief of the train pipe pressure or any other degree of 50 relief of that pressure as may be desired. Any form of abutment or means for adjustably limiting the throw of the lever 8 will suffice and be equally within my invention. On the locomotive, preferably on the 55 front trucks, I suspend a contact or brush 23 which is adapted to make contact with a track contact or third rail 24. Contact or brush 23, which may be of any desired form or material, but preferably a metallic brush, 60 is mounted in and insulated from an arm 25 pivoted to the frame 26 of the truck, or said contact may be carried by the locomotive in any other suitable manner.

Track contact or third rail 24 may be of 65 any suitable form and length and may be

placed on the ties by the side of one of the rails as shown in Fig. 8. To assure a simple structure and one easily applied to any railway, I prefer to construct the track contact or third rail of T iron 27 of any desired length and to support it on and insulate it from the ties or ground in any convenient manner, as by wooden block 28 having a longitudinal groove 29 into which the depending limb of the T iron is inserted, a feather or lug 30 on one side of said limb engaging another groove 31 made in block 28. Block 28 is supported on the tie by suitable plates 32 which are bolted together by bolts 33 and suitably fastened to the tie. These supporting blocks 30 and plates may be provided at as many points on track contact or third rail 24 as may be convenient or necessary to properly support the same.

A circuit wire 34 leads from electro-tripping magnet 5 to one of the axles 35 or frame of the locomotive, another circuit wire 36 leads from the magnet to contact or brush 23. Another circuit wire 37 leads from one side of battery 38 to one rail of the track and another circuit wire 39 leads from the other side of battery 38 to track contact or third rail 24. A switch 40 is placed in one of these circuit wires 37 and 39. Battery 38 and switch 40 may be located in any convenient place, preferably in the operator's tower where they will be within easy reach of the operator when their use is required.

The operation of my arrangement will be apparent from the description. In detail it is as follows: Valve 4 is normally seated by the train line pressure of the air brake system. As the car reaches the point on the track where the third rail 24 is placed, contact or brush 23 rides on the track contact or third rail 24 and makes contact therewith. But electro-tripping magnet 5 is not energized, switch 40 being open. The car therefore proceeds without interference. But if, for any reason, the operator wishes to control the train, he closes switch 40 and the circuit is closed between both sides of battery 38, including the track contact or third rail 24, contact or brush 23, circuit wire 36, electro-tripping magnet 5, circuit wire 34, the axle and wheel or frame of the locomotive, one rail of the track and circuit wire 37. Electro-tripping magnet 5 is thus energized, latch 7 is actuated to release lever 8, which is forced by spring 13 against valve 4. Valve 4 is thereby opened, the fluid pressure in the train pipe is more or less released, and a signal or application of the brakes is made according to the position of abutment 8^b and the train is thereby controlled.

It is obvious that my device may be attached to any car of a train as well as to the locomotive, or to an electric car, or to any car of an electric train, and be equally within my invention. It is also obvious that track

contact or third rail 24 may be of any desired length and placed at any desired point or points on the track or tracks. It may be placed on the track on both sides of the ordinary operator's tower so that in case he should receive an order to stop a train while it is passing his tower, he may yet signal or stop it and prevent any accident.

Many modifications will be obvious to one skilled in the art. Any form of relief means will come equally well within my invention; consequently I do not wish to be confined to the exact forms of construction or arrangement of parts described and shown.

15. What I claim is:

1. In apparatus of the class described the combination of a car, a track, a track contact, a pressure relief valve connected to the train pipe of the air brake system on the car, 20 an electro-tripping magnet on the car, a lever adapted to operate the valve and to be released by the magnet, means for adjustably limiting the throw of the lever, a normally open circuit on the car including the magnet, 25 a contact carried by the car and the car frame or axle, a normally open circuit at a predetermined point on the track including the track contact, a battery and one rail of said track and means for manually closing said circuits 30 when the car reaches said predetermined point.

2. In apparatus of the class described the combination of a car, a track, a track contact, a pressure relief valve on the car, an 35 electro-tripping magnet on the car, a lever adapted to operate the valve, an adjustable means for limiting the throw of the lever, a latch normally engaging said lever, a circuit including the magnet, one rail of the track, 40 a battery, the track contact and a switch adapted to close said circuit, to energize the magnet and release the lever to operate the valve.

3. In apparatus of the class described the 45 combination of a car, a track, a track contact, a pressure relief valve normally held on its seat by the train pipe pressure of the air brake system, a normally deenergized electro-tripping magnet on the car, means adapted 50 to be released by said magnet for mechanically and adjustably operating said valve, a normally open circuit at a predetermined point on the track including the magnet, the track contact, a source of electric energy and 55 the track rails and means for closing said circuit.

4. In apparatus of the class described the 60 combination of a car having an air brake system, a track, an electro-magnet mounted on the car, a pressure relief valve on the car nor-

mally seated by the train pipe pressure of the air brake system, means adapted to be released by the magnet for adjustably unseating the valve and means for energizing the magnet at a predetermined point on the 65 track.

5. In apparatus of the class described the combination of a car, a track, a track contact, an electro-tripping magnet on the car, a pressure relief valve in communication with the train pipe pressure of the air brake system on the car, a lever normally engaged by a latch, means opposing the lever, a guide having an adjustable abutment to limit the throw of the lever, a circuit at a predetermined point on the track, including the magnet, the track contact, a battery and one rail of the track, and a switch adapted to close the circuit to energize the magnet. 75

6. In apparatus of the class described the combination of a car, a track, a track contact, an electro-magnet on the car, a pressure relief valve having two independent areas normally exposed to and seated by the train pipe pressure of the air brake system on the 85 car, one of said areas being less than the other, means actuated by the magnet for first moving the lesser area off its seat to relieve the pressure on the larger area, means for controlling the movement of both areas to relieve a predetermined quantity of the train pipe pressure, a circuit, at a predetermined point on the track, including the magnet, the track contact, a battery and one rail of the track, and a switch adapted to close circuit 90 95 to energize the magnet.

7. In apparatus of the class described the combination of a car, a track, an electro-tripping magnet on the car, a pressure relief valve in communication with the train pipe 100 of the air-brake system on the car, means adapted to be actuated by the magnet for operating the valve, a track contact consisting of a T having a feather or lug on the depending leg, an insulating block provided 105 with a recess for receiving the depending leg of the T; a slot in the block for receiving the feather or lug and means for retaining and supporting the block, a circuit at a predetermined point in the track including the magnet, the track contact, a battery, one rail of the track, and a switch adapted to close the circuit to energize the magnet. 110

In witness whereof I hereunto subscribe my name in the presence of two witnesses.

AUGUST W. REILING.
